UNITED STATES PATENT OFFICE.

ABRAHAM NOVICK, OF BROOKLYN, NEW YORK, ASSIGNOR TO F. L. SCHMIDT COMPANY, OF NEW YORK, N. Y., A CORPORATION OF NEW YORK.

WASHER AND STRING ATTACHING MECHANISM.

1,104,128.

Specification of Letters Patent. Patented July 21, 1914.

Application filed May 15, 1914. Serial No. 838,676.

To all whom it may concern:

Be it known that I, ABRAHAM NOVICK, a citizen of the United States, and a resident of New York, borough of Brooklyn, in the county of Kings and State of New York, have invented certain new and useful Improvements in Washer and String Attaching Mechanisms, of which the following is a specification.

10 This invention relates to washer and string attaching mechanisms and is particularly directed to means for attaching to the bodies or flaps of envelopes, or the like, one or more washers with a tie string fastened thereto by means of an eyelet.

The object of my improved mechanism is to provide means simple in construction, and rapid and reliable in operation for fixing to a sheet of material one or more washers and a piece of string.

20 A further object of my improvements is to deliver one of the washers into setting position with the string passed through a hole in said washer, whereby greater security of 25 the string is obtained and a more reliable tie envelop produced, all in one operation.

With these objects in view my improvements comprise parts and combinations of parts illustrated in their preferred form in 30 the accompanying drawings wherein—

Figure 1 is a front elevation, partly in section, of the mechanism embodying my improvements. This figure is in some respects diagrammatic and the means for connecting and timing the several sub-mechanisms is omitted as being unnecessary for the present purpose and within the knowledge of those skilled in the art to which this invention pertains. Figs. 2 and 3 are 40 elevations showing a portion of what is shown in Fig. 1, but illustrating the successive steps in the operation. Fig. 4 is an enlarged section through the center of the eyelet and illustrating the work produced 45 by my improved mechanism. Figs. 1, 2 and 3 are to the same scale and Fig. 4 is to a larger scale.

50 Directing attention now particularly to Fig. 1, there is therein shown an eyelet setting anvil comprising post 2 and floor 3. Said post is efficient for centering a bottom washer 4 having a hole centrally therethrough and floor 3 is efficient for supporting said washer. Directly above said post

2, and ready to be lowered thereon, is a sheet of material 5 and which may represent the flap of an envelop to which it is desired to fix a washer or washers as 6, 6 and a length of string 7, by means of the usual eyelet 8 (Fig. 4). Said sheet of material 5 has previously been provided with a hole 9 therethrough for the reception of eyelet 8. Directly above said anvil post 2 and mounted in bearing 11 for reciprocation toward and from said anvil is punch 10. Mounted in the lower end of said punch 10 is eyelet engaging needle 12. Said needle is mounted for reciprocation lengthwise of said punch and is urged outwardly thereof by spring 13. Punch 10 may be reciprocated in its bearing 11 by means of arm 20 pivoted on stud 21. Said arm is bifurcated at its free end and engages pin 22 fixed in the upper end of said punch. Arm 20 may be oscillated to reciprocate punch 10 by means of link 23 pivoted thereto at 24.

For feeding the eyelets as 8 one at a time into the path of said needle and punch, I provide chute 14. Said chute is attached to agitator 15 and hopper 16 and is pivotally mounted on stud 17. Said chute may be retracted to the right, Fig. 1, by means of link 18, pivotally attached to arm 19 of said chute.

Top washers as 6 are supported by a reservoir which preferably comprises rod 25 having a hole 26 lengthwise therethrough for the passage of string 7 from its source of supply 27. Said rod 25 may be supported in bracket 28 outstanding from bearing 11. For delivering said top washers one at a time with the string therethrough from off the bottom of rod 25 to a position in line with punch 10 and end eyelet 8 in delivery position, I provide slide 29 mounted for reciprocation in a plane transverse the line of reciprocation of said punch 10. Said slide 29 is provided with seat 30 for the reception of the lowermost washer 6 in said reservoir. Said seat is of a depth slightly less than the thickness of a washer so that when slide 29 is moved to the right, Fig. 2, washer 6a directly above the lowermost washer 6, will remain unmoved. Slide 29 may be reciprocated by means of bell crank lever 31 pivoted on stud 32. Said lever is bifurcated at its lower end and engages pin 33 fixed in ear 34 of said slide. Bell crank

lever 31 may be rocked on its pivot 32 by means of link 41 pivoted thereto at 35.

For measuring and cutting string 7 into suitable lengths, I provide gage 36. Said 5 gage is slotted at 37 and is adjustably fixed to post 38 by means of screw 39. The right hand end of said gage 36 is provided with knife 40 against which the string may be pressed and severed.

10 The operation of my improved mechanism is as follows: The bottom washer 4 having been placed over post 2, a sheet of material 5 is introduced to the position shown in Fig. 1, over said post. Eyelet chute 14 having been charged with eyelets, the lowermost one, 8 thereof, is forced by the other eyelets thereabove to a position in the end of said chute and directly under needle 12; also slide 29 being in its retracted position has 15 received lowermost washer 6 in seat 30. Said slide 29 is thereupon moved forwardly to a position under needle 12, said washer sliding along string 7 in its progress. Next, punch 10 is lowered, Fig. 2, projecting 20 needle 12 through eyelet 8 and through washer 6, crowding string 7 to one side of the opening through said washer, and the point of said needle engages the dished top of anvil post 2. Thereupon chute 14 is 25 swung to the right, thereby freeing eyelet 8 and leaving it strung upon needle 12. Directly thereafter slide 29 is retracted, when washer 6 with the string therethrough and eyelet 8 thereabove, slide down needle 12 30 onto sheet 5. Punch 10 then continues its descent, needle 12 retracting therein and compressing spring 13. When punch 10 encounters the flanged side of eyelet 8 it drives the body portion of that eyelet through 35 washer 6, sheet 5 and lower washer 4 and presses said eyelet against the anvil, thereby locking upper washer 6 with string 7 therethrough, sheet 5 and lower washer 4 securely together. Punch 10 is then retracted to the 40 position of Fig. 1 and sheet 5 is carried by hand to the right until the left hand edge of eyelet 8 is directly below knife 40, where the string is cut as shown at 42, Fig. 4, close to said eyelet. The carrying of said sheet 5 45 to the right as described draws a new portion of string through hollow rod 25, in position and of a suitable length for use in the next operation of the machine.

I claim:

55 1. In a mechanism of the character described, the combination of a washer reservoir having a string passage lengthwise therethrough, means for delivering a washer with a string therethrough from said reservoir into setting position, and means for securing said washer and string to a sheet of material.

2. In a mechanism of the character described, the combination of an eyelet setting anvil, a reciprocating punch for coac-

tion with said anvil, means for delivering eyelets one at a time into the path of said punch, a washer reservoir having a string passage lengthwise therethrough, and means for delivering a washer with a string therethrough from said reservoir under said eyelet between said punch and anvil.

3. In a mechanism of the character described, the combination of an eyelet setting anvil, a reciprocating punch for coaction with said anvil, an eyelet engaging needle carried by said punch and yieldable in the direction of the reciprocation of said punch, means for feeding eyelets one at a time into the path of said needle and punch, a washer reservoir having a string passage lengthwise therethrough, and means for delivering a washer with a string therethrough from said reservoir to a position under the eyelet between said punch and anvil.

4. In a mechanism of the character described, the combination of an eyelet setting anvil having means thereon for supporting and centering a bottom washer, a reciprocating punch for coaction with said anvil, an eyelet engaging needle carried by said punch and yieldable in the direction of the reciprocation of said punch, means for feeding eyelets one at a time into the path of said needle and punch, means for retracting the eyelet feeding means from the path of said punch, means for reciprocating said punch, a top washer reservoir having a string passage lengthwise therethrough, and means for delivering a top washer with a string therethrough from said reservoir to a position under the eyelet between said punch and anvil.

5. In a mechanism of the character described, the combination of an eyelet setting anvil, a reciprocating punch for coaction with said anvil, an eyelet engaging needle carried by said punch and yieldable in the direction of the reciprocation of said punch, an eyelet chute for feeding eyelets one at a time into the path of said needle and punch, means for retracting said eyelet chute from the path of said punch, a washer reservoir having a string passage lengthwise therethrough, means for delivering a washer with a string therethrough from said reservoir to a position under the eyelet between said punch and anvil, and means for retracting said washer delivery means.

6. In a mechanism of the character described, the combination of an eyelet setting anvil, a reciprocating punch for coaction with said anvil, an eyelet engaging needle carried by said punch and yieldable in the direction of the reciprocation of said punch, means for feeding eyelets one at a time into the path of said needle and punch, a washer reservoir having a string passage lengthwise therethrough, means for delivering a washer with a string therethrough

from said reservoir to a position under the eyelet between said punch and anvil, and means for measuring and cutting said string.

7. In a mechanism of the character described, the combination of an eyelet setting anvil, a reciprocating punch for coaction with said anvil, an eyelet engaging needle carried by said punch and yieldable in the direction of the reciprocation of said punch, means for feeding eyelets one at a time into the path of said needle and punch, a washer reservoir having a string passage lengthwise therethrough, means for delivering a washer with a string therethrough from said reservoir to a position under the eyelet between said punch and anvil, means for measuring and cutting said string, and means for adjusting the string measuring means.
- 20 8. In a mechanism of the character described, the combination of an eyelet setting anvil having means thereon for supporting and centering a bottom washer, a reciprocating punch for coaction with said anvil, an eyelet engaging needle carried by said punch and yieldable in the direction of the reciprocation of said punch, an eyelet chute for feeding eyelets one at a time into the path of said needle and punch, means for retracting said eyelet chute from the path of said punch, a top washer reservoir comprising a rod on which washers are strung, a string passage lengthwise through said rod, a reciprocating slide for advancing a top washer with a string therethrough from the reservoir to a position in line with the reciprocation of said needle, means for reciprocating said slide, and an adjustable cutting gage for said string.
- 35 9. In a mechanism of the character described, the combination of an eyelet setting anvil, a reciprocating punch for coaction

with said anvil, an eyelet engaging needle carried by said punch and yieldable in the direction of the reciprocation of said punch, means for feeding eyelets one at a time into the path of said needle and punch, a washer reservoir comprising a rod on which washers are strung, a string passage lengthwise through said rod, means for delivering said washers one at a time with a string therethrough from said reservoir to a position in line with said punch and under the eyelet, and an adjustable cutting gage for said string.

10. In a mechanism of the character described, the combination of an eyelet setting anvil having means thereon for supporting and centering a bottom washer, a reciprocating punch for coaction with said anvil, an eyelet engaging needle carried by said punch and yieldable in the direction of the reciprocation of said punch, an eyelet chute for feeding eyelets one at a time into the path of said needle and punch, means for retracting said eyelet chute from the path of said punch, means for reciprocating said punch, a top washer reservoir comprising a rod on which washers are strung, a string passage lengthwise through said rod, a reciprocating slide for advancing a top washer with a string therethrough from the reservoir to a position in line with the reciprocation of said needle, means for reciprocating said slide, and an adjustable cutting gage for said string.

Signed at Chicago, in the county of Cook and State of Illinois, this 12th day of May, 1914, before two subscribing witnesses.

ABRAHAM NOVICK.
